UNITED STATES PATENT OFFICE.

ERNEST J. JONES, OF BALTIMORE, MARYLAND.

HAME-FASTENER.

958,253.

Specification of Letters Patent. Patented May 17, 1910.

Application filed June 5, 1909. Serial No. 500,289.

To all whom it may concern:

Be it known that I, ERNEST J. JONES, a citizen of the United States, residing at Baltimore, in the State of Maryland, have 5 invented certain new and useful Improvements in Hame-Fasteners, of which the following is a specification.

My invention relates to hame-fasteners, and the objects thereof are to provide a device of the character described which when applied to the ends of a hame will preclude any possibility of the latter becoming accidentally disconnected; to provide a hame-fastener in which the locking action of its 15 constituents is increased proportionately to the amount of stress exerted thereon; to provide an operating lever which will serve the dual function of assisting in the manipulation of the connecting members and as an 20 additional means for preventing the separation of the ends of the hame; to devise a hame-fastener which is adjustable according to the variance in contour of a horse's neck; to insure a means for expeditiously disconnecting the hame-fastener; and to otherwise 25 arrange and construct the component parts thereof so that the same may be manufactured and sold at a minimum cost and adapted generally for the purpose for which 30 it is devised.

To the accomplishment of the recited objects and others coördinate therewith, the preferred embodiment of my invention resides in that construction and arrangement 35 of parts hereinafter described, illustrated in the accompanying drawings, and embraced within the scope of the appended claims.

In said drawings:—Figure 1 is a side elevation of the hame-fastener embodying my 40 invention. Fig. 2 is a similar view showing one of the members swung outwardly. Fig. 3 is a top plan view of one of the members, and Fig. 4 is a bottom plan view of the lever.

Similar reference characters designate corresponding parts throughout the several 45 views.

Essentially, my invention comprises in its construction and arrangement members 1 and 2 and a lever 3.

50 The members 1 and 2 are similar in that their upper extremities form snap hooks, respectively designated by the numerals 4 and 5, and in other respects these members differ. The lower extremity of member 1 is bifurcated and the parallel portions constituting 55 the bifurcation are equipped with a plu-

rality of notches 7, which are disposed in alinement in such manner as to provide a rack. The other member 2 is characterized by a curvilinear lower terminal 8, the terminal 60 portion of which is flattened and otherwise rabbeted, as at 9, and suitably apertured to receive the pin 10 when said flattened portion is positioned intermediate the bifurcated end 11 of the lever 3, the said pin 65 manifestly also extending through the bifurcated terminal of the lever 3 so as to insure a pivotal connection for these parts.

The lever 3, near its hinged end, has a lug or projection 12 extending from diametrically opposite sides, each of said projections having a knob 13 which is designed to prevent lateral play or displacement of said lever when the projections 12 occupy their normal positions in the notches 7 of the 70 member 1. The enlarged upper terminal 14 of the lever 3 is reversely bent and is provided with a hook-like recess 15, the latter being designed for engagement with the link 16, pivoted to and depending from the 80 hooked end of member 2, the underneath surface of which is flattened, as at 17, and is adapted to normally lie contiguous the opposed surface of lever 3.

In practice, the fastener occupies substantially the position with respect to the hame, as shown in Fig. 1 of the accompanying drawings. Owing to the fact that the connecting point of the member 2 and the lever 3 is below the axis formed by the lugs 85 or trunnions 12, the rack of member 1 and the correlative disposition of the lower terminal of member 2, the stress which is exerted on the snap hooks 4 and 5 will cause the angularly deflected portion 14 of the lever 3 to engage the flattened portion 17 of the snap hook 5 and in this manner create a locking means, the efficiency of which is increased according to the increment of the pull on the snap hooks 4 and 5. While ordinarily this locking means answers the purpose, if for any reason the pull on members 4 and 5 is not sufficient to produce the locking connection, the lever 3 will gravitate until it contacts with the link 16, whereby the 95 latter engages the hook-like recess 15, and in a sense, automatically locks and precludes any possibility of the parts becoming separated. It will also be noted that the maximum latitude of movement results from such 100 an assemblage of parts. When it is desired to attach or detach the members 1 and 2, to 105 110

or from, the ends of the hame this operation may be secured with facility. As will be found upon inspection of Fig. 2 of the drawings, the member 2 is distended a suitable 5 distance by the simple operation of lowering or pulling down upon the lever 3. Other advantages may be assigned to this feature, among which it will be well to bear in mind, the fact that the member 1, and member 2 10 and lever 3, which will be considered as an entirety, may be readily disconnected when the occasion so requires.

What I claim is:—

A hame-fastener comprising a pair of members and a lever, the upper extremities of said members constituting snap hooks, the lower terminal of one member having a rack, said lever being provided with trunnions for engagement with said rack and pivotally connected to the lower terminal of the other 15 20

member at a point below said trunnions, whereby the upper terminals of the last mentioned member and the lever are normally held in engagement with each other, but adapted to become disengaged when the 25 pull on said members is released, said lever having a hook-like recess at its upper end, and the end of the hooked portion of the last mentioned member having a pivoted link which surrounds the upper end of said 30 lever and is adapted to enter said recess when said member and lever become disengaged.

In testimony whereof I affix my signature, in presence of two witnesses.

ERNEST J. JONES.
